UNITED STATES PATENT OFFICE.

SPOTSWOOD D. BOWERS, OF BRIDGEPORT, CONNECTICUT.

GAME APPARATUS.

No. 878,334.

Specification of Letters Patent.

Patented Feb. 4, 1908.

Application filed June 12, 1907. Serial No. 378,531.

To all whom it may concern:

Be it known that I, SPOTSWOOD D. BOWERS, a citizen of the United States, residing at Bridgeport, in the county of Bridgeport 5 and State of Connecticut, have invented certain new and useful Improvements in Game Apparatus, of which the following is a specification.

This invention relates to improvements in 10 game apparatus, and the object is to provide a novel game apparatus, by means of which an amusing and interesting game may be played.

The invention consists in the novel features of construction hereinafter fully described, particularly pointed out in the claims, and clearly illustrated by the accompanying drawings, in which—

Figure 1 is a plan view of the game board, 20 and Figs. 2 and 3, views of the game pieces.

The game apparatus comprises a board 1 arranged upon which is a zig-zag course or path 2 starting at one side of the board and terminating at the opposite side, said path 25 being formed of representations of animal tracks, and having at intervals, tracks 3, which are colored differently from the other tracks of the path or otherwise distinguished therefrom, said tracks 3 being what I term 30 "capture points."

Starting at a point at the same side of the board as the starting point of the path 2 and terminating at the opposite side of the course at the finishing point of said path 2 are a 35 number of paths or courses 4, which intersect the zig-zag path 2, the points of intersection being at the capture-points 3. Intersecting the several paths 4 are paths 5, connecting the several paths 4, as illustrated. Paths 40 and 5 are formed of representations of human footprints.

In the present instance, the game is designed to represent a bear-hunt, in which a game-piece representing the bear is moved 45 by successive moves over the zig-zag path 2 from the starting point, the distance moved on each play being determined, as is common in games of this character, by throwing dice. The game pieces representing the hunters, 50 of which there may be several, are moved along paths 4 and 5, either back or forth,

beginning at the indicated starting place, the moves of the hunters being governed by the throwing of dice as in the case of the bear. If the bear can be overtaken on one of the 55 capture points 3, the player so succeeding is the winner of the game. The capture is effected by the move of the player terminating on one of the capture points when the bear is on that point, or vice versa. If this 60 capture is not effected before the bear reaches the finish, the player whose game-piece first reaches the finish is the winner.

While I have illustrated and described the game-board as adapted to playing a game 65 representing a bear-hunt, it is apparent that other games might be played in which the principal features of the invention might be utilized without departing from the spirit and scope of my invention.

Having thus fully described my invention, what I claim as new, and desire to secure by Letters Patent of the United States, is:—

1. A game apparatus comprising a game-board having a zig-zag path represented 75 thereon provided at intervals with distinguishing points, and having a number of paths intersecting the zig-zag path, the point of intersection being at said distinguishing points.

2. A game apparatus comprising a game-board having represented thereon a zig-zag course or path having a start and a finish and provided at intervals throughout its extent with distinguishing points, a number of irregular paths extending across the board and 85 intersecting said zig-zag path at several points, the points of intersection being at said distinguishing points.

3. A game apparatus comprising a game-board having represented thereon a zig-zag 90 path extending thereacross and provided at intervals with distinguishing points, a number of paths extending across the board and intersecting said zig-zag paths at the distinguishing points and a number of paths arranged to connect the last-mentioned path at several points.

4. A game apparatus comprising a game-board having thereon a zig-zag path consisting of the representation of animal tracks 100 having at intervals a track colored or marked to distinguish it from the remainder of the

tracks, a plurality of paths intersecting the zig-zag path at said distinguishing tracks, said paths being formed of representations of human footprints, and connecting paths connecting said last mentioned paths at several points, said connecting paths being designed to represent human footprints.

In testimony whereof I affix my signature, in presence of two witnesses.

SPOTSWOOD D. BOWERS.
